UNITED STATES PATENT OFFICE

120,932

DESIGN FOR A PNEUMATIC TIRE CASING

A. Houston Holland, Enid, Okla., assignor to
Champlin Refining Company, Enid, Okla., a
corporation of New Mexico

Application February 5, 1940, Serial No. 90,048

Term of patent 7 years

To all whom it may concern:

Be it known that I, A. Houston Holland, a citizen of the United States, residing at Enid, in the county of Garfield and State of Oklahoma, have invented a new, original, and ornamental Design for a Pneumatic Tire Casing, of which the following is a specification, reference being had to the accompanying drawing, forming part thereof.

Figure 1 is a perspective view of a pneumatic tire casing showing my new design.

Figure 2 is a transverse sectional view taken substantially on the line 2—2 of Figure 1.

I claim:

The ornamental design for a pneumatic tire casing, as shown.

A. HOUSTON HOLLAND.
